UNITED STATES PATENT OFFICE.

EDWARD S. COBB, OF WHITTIER, CALIFORNIA, ASSIGNOR TO COBB SHOCKLESS CROSSING CORPORATION, OF NEW YORK, N. Y., A CORPORATION OF NEW YORK.

RAILROAD INTERSECTION.

1,252,664.

Specification of Letters Patent.

Patented Jan. 8, 1918.

Application filed March 6, 1917. Serial No. 152,523.

To all whom it may concern:

Be it known that I, EDWARD S. COBB, a citizen of the United States, residing at Whittier, in the county of Los Angeles, State of California, have invented new and useful Improvements in Railroad Intersections, of which the following is a specification.

This invention relates to railroad intersections; relating particularly to intersection mechanisms whereby a smooth continuation of either of the intersecting tracks is made across the intersection; or whereby the flange openings or spaces are done away with (filled) for either of the intersecting tracks. And this invention comprises particularly the provision, in such an intersection mechanism, of means for making the intersection, whenever so desired, an ordinary intersection for use in the usual manner. Such intersections as I here refer to, and describe one particular form of herein-after, are usually operated in a block system or are operated automatically by approaching trains, and any disability of such operating mechanism may temporarily disable the intersection. It is an object of this invention to provide means for quickly and easily transforming or changing the intersection mechanism into such form as to be effective as an ordinary intersection with the usual flange openings or spaces in the rails. It is an object of this invention to provide such a means in simple and easily operated form, and in such a form as to not interfere with the effective normal operation of the crossing mechanism; so that the crossing mechanism may normally operate at the highest efficiency, but be quickly changeable in an emergency for temporary use.

My invention may take various forms. In its broad aspect it embodies an intersection mechanism adapted to make a continuous passage for either of two tracks across an intersection in combination with, or including, means for rendering the intersection mechanism an ordinary intersection or crossing. In this following specification I explain a combination of one character including my invention and direct the claims to the broad features of the invention and also to the specific features herein specifically set forth; while in a co-pending application S. N. 152,522, filed March 6, 1917, I

set forth another form of my invention and therein specifically claim that form.

Although my present invention may be applied to various forms of intersection mechanisms, I herein explain my invention in connection with that form of intersection mechanism which utilizes two pairs of vertically movable rail portions, each preferably extending integrally between rail intersections with mechanism to alternately raise and lower the said pairs of vertically movable rail portions. (This form of intersection mechanism is the subject matter of the claims of a co-pending application on railroad intersection, S. N. 156,024, filed March 20, 1917.) For this particular form of intersection mechanism, my present invention takes the form of removable blocks at the ends of the vertically movable rail portions, adjacent the rail intersections; and of means for temporarily supporting the movable rail portions in position to simultaneously form continuations of the rails of both the intersecting tracks. I proceed to a detailed description of this preferred and specific embodiment of my invention, reference being had to the accompanying drawings in which, for the purpose of this specification, I have illustrated said preferred and specific embodiment of my invention. In these drawings Figure 1 is a plan of my improved railroad intersection, parts being broken away for purposes of illustration; Fig. 2 is a vertical cross section taken as indicated by line 2-2 on Fig. 1; Fig. 3 is a vertical cross section taken as indicated by line 3-3 on Fig. 2; Fig. 4 is a detailed vertical section taken as indicated by line 4-4 on Fig. 1; Fig. 5 is a detail section taken as indicated by line 5 on Fig. 4; Fig. 6 is a similar section showing the adaptation of a removable block to an ordinary form of rail; Fig. 7 is a plan showing a movable rail portion equipped with a modified form of removable block; Fig. 8 is a side elevation of the same; and Fig. 9 is an enlarged central longitudinal section of the same.

In the drawings the numeral 10 designates a suitable box structure forming the base and frame upon and in which the crossing intersection mechanism is mounted; and the letters A and B indicate the rails of two intersecting tracks. These tracks are shown intersecting at right angles, but it will be

understood that they may intersect at any angle without changing the operation of the mechanism herein described. It will be seen that the following description includes a mechanism for forming a continuation across the intersection of either the rails A or the rails B, and a means for modifying or changing the effect of this said mechanism so that a device is presented which is, to all intents and purposes of use, an ordinary crossing.

The intersection mechanism which forms a continuation of the rails of either one track or the other across the intersection, may be briefly described as follows: The rails A and B are securely and permanently attached to the box structure 10, so as to be stationary; and at the individual rail intersections, where these stationary rails A and B meet each other, they are provided with diagonal end planes 20, which planes form the surfaces at which the rails A and B meet each other, and also form the surfaces at which the movable rail portions A' and B' meet the stationary rails. These movable rail portions A' and B' also have similar diagonal surfaces 20 at their ends which bear against each other and bear against the surfaces 20 of the fixed rails A and B. At each intersection the diagonal surfaces 20 do not proceed to the center of the rail intersection; but at the center of each rail intersection there is a square block 21 which may be formed integrally with one of the stationary rails. The movable rail portions A' and B' abut this square block 21 as illustrated. Beneath one pair of the movable rail portions, in this case the rail portions A', I locate horizontal cam shafts 22. These shafts are mounted in terminal bearings 23 and carry the cams 24 which support the movable rails B'. Each movable rail B' has supporting beams 25 which rest upon the two opposite cams 24 so that these rail portions B' are supported by the cams, and raised and lowered by their action.

The cams 30 are also mounted upon the shaft 22, but are preferably mounted upon the shaft in such a manner as to be relatively movable thereon to change the relation of cams 30 to cams 24, for the purpose herein-after described. These cams 30 are accordingly mounted upon sleeves 31 which surround the shafts 22 and may be normally fastened to the shafts by such means as a screw or plug as shown at 32. These adjustable sleeves 31 are mounted in the bearings 33, as illustrated. To all usual intents and purposes sleeve 31 and its shaft 22 form one solid shaft upon which the cams 24 and 30 are mounted; the adjustability of position of the sleeve 31 on shaft 22 being called into play only when the intersection mechanism is set to provide an ordinary crossing. Upon each of the sleeves 31 I mount drum

35 and rotatively connect these two drums by a pair of crossed chains 36. The vertically movable rail portions A' have feet 35 resting upon the cams 30; so that these rail portions are supported by, and raised and lowered by, the cams 30. Each of the cams has an undercut in its outer face, as shown at 36, and members 37 on feet 25 and 35 engage beneath these undercuts and cooperate with them so as to pull the movable rail portions down when the cams act to lower the movable rail portions.

It is unnecessary for the purposes of this specification, to go into further detail with regard to the exact structure of the intersection mechanism. Sufficient has been explained to show the primary features of such a mechanism, and to show how, by rotation of shafts 22, the action of the cams 24 and 30 is to lower one set of rails and raise the other set of rails upon rotation in one direction, and to raise the first mentioned set and lower the second mentioned set upon rotation in the other direction. For instance, in the drawings the rail portions B' are shown in their elevated positions, in positions to form continuations of the stationary rails B; while the rail portions A' are shown depressed. Upon rotation of the shafts 22, with cams 24 and 30, in the directions indicated in Fig. 2, and through an angle equal to approximately three quarters of a revolution, the rails B' will be lowered and rails A' will be raised. In other words, the cams 24 and 30, which are essentially duplicates of each other, are so placed on the shaft that approximately three-quarters of a revolution is required to carry the shaft from a position where the highest part of one cam is beneath a rail foot to a position where the highest part of another cam is beneath its rail foot. Consequently, if it is desired to adjust the mechanism so as to simultaneously support all of the movable rails in their uppermost positions, then it is only necessary to turn the sleeves 31 on the shafts 22 through approximately three-quarters of a revolution. This may be effected by withdrawing the locking pins 32 from their positions shown in the drawings, rotating the shafts and sleeves relatively through the angle noted, and then inserting the pins through the apertures provided at 40, said apertures being placed in the sleeves and shafts in such position as to cause proper registry of the cams 24 and 30. When this is done, then both pairs of vertically movable rail portions A' and B' may be supported simultaneously in their uppermost position.

Provision for simultaneously supporting the movable rail portions may be made in other manners. For instance, I may merely lift the pair of rails which is lowermost, say the pair of rails A', and place supporting blocks between the feet 35 and the cams 30.

The rails now all being in their uppermost positions, and forming continuations of the stationary rails A and B, it is necessary to provide open spaces for the passage of wheel flanges. This is done by providing removable blocks 50, one at each end of each movable rail portion. A preferred form of construction for this removable block is shown in Figs. 4 and 5. The block 50 has a back-
wardly inclined bottom face 51 which rests upon a correspondingly inclined surface at the end of the rail portion. The block also has two downwardly descending side portions 52, as is best shown in Fig. 5; and these side portions straddle the web 53 of the rail and rest at their lower ends upon horizontal shoulders 54 of the rail. A screw or bolt 55 serves to hold the block in place; but this screw does not carry any of the operating strain. It will be noted that the removable block is firmly bedded upon the surfaces 51 and 54; and the surface 51 is of such shape that all weight upon the block tends to move the block back against the back surface 56 rather than to move the block out away from the rail portion upon which it is mounted. Thus, although the blocks may be more easily removed, they are also very solidly supported in their normal operating position. The outer ends of these blocks are provided with the bearing surfaces 20, as hereinbefore described as at the ends of the movable rail portions.

I show the rails A' and B' each as being made up of beams 70 in and on which a rail head 71 and web 53 are set and carried; being held to the beam by screws 72 or the like. In Fig. 5 the block 50 is shown resting on the surface 51 which is an upper surface on web 53, and resting on shoulders 54 which are on the beam 70. Now, the rails A' and B' may be in ordinary rail form, as shown in Fig. 6; in which case the block 50 rests on the surface 51 as before, but rests, at the lower ends of the side extensions 52, on the upper surfaces of rail flange 75 on opposite sides of the rail web 76. Such variations may be made without materially altering the nature of the mechanism.

In Figs. 7-9 I show another form of block 50^a set in the end of the movable rail portion (A') and secured by a screw 60 having a conical head 61 entering a correspondingly shaped opening in the block 50^a. A suitable lock washer, as at 62, may be used to prevent the screws and block loosening from position.

It will now be seen how an intersection mechanism of the character described may normally operate to provide a continuation of either the rails of one or the other track; and how, in an emergency, all the rails may be raised and the blocks 50 removed to form an ordinary crossing. Although I have pro-
ceeded to explain this device in some detail,

I have done so in order to make my invention understood, and not because I consider my present invention as limited to the particular kind of intersection mechanism herein described. In fact, as indicated and particularly set out in the following claims, I consider my invention to be of a broad nature; its fundamental feature being the arrangements or means enabling me to make the transformation herein described. 70

Having described a preferred form of my invention, I claim:

1. In a railroad intersection, in combination with a pair of intersecting tracks, movable rail portions between the individual rail intersections, and removable blocks on said movable rail portions adjacent the rail intersections and adapted to be removed to make openings for passage of flanged wheels. 75

2. In a railroad intersection, in combination with a pair of intersecting tracks, movable rail portions extending integrally between the individual rail intersections and movable as single units, and removable blocks on said movable rail portions adjacent the rail intersections and adapted to be removed to make openings for passage of flanged wheels. 85

3. In a railroad intersection, in combination with a pair of intersecting tracks, movable members adapted to form continuations of the rails of the tracks, means to move said members to form continuations of the rails of either one or the other of said tracks, and means removable from said members to leave 100 open spaces adjacent the rail intersections for passage of flanged wheels on both tracks. 95

4. In a railroad intersection, in combination with a pair of intersecting tracks, movable rail portions between the individual rail intersections, means to move said rail portions so as to make continuations of the rails of either one track or the other, means to move said rail portions to form continuations of the rails of both tracks, and removable parts on said rail portions adapted to be removed to make openings for passage of flanged wheels. 110 105

5. In a railroad intersection, in combination with a pair of intersecting tracks, movable members adapted to form continuations of the rails of the tracks, means to move said members to form continuations of the rails of either one or the other of said tracks, means to move said members to form continuations of the rails of both tracks, and means removable from said members to leave open spaces adjacent the rail intersections for passage of flanged wheels over both tracks. 115 120

6. In a railroad intersection, in combination with a pair of intersecting tracks, vertically movable rail portions adjacent the individual rail intersections, means to move said rail portions to form continuations of 130

- the rails of either one or the other of said tracks, means to support said rail portions to form continuations of the rails of both tracks, and removable parts on the movable rail portions at the rail intersections.
7. In a railroad intersection, in combination with a pair of intersecting tracks, vertically movable rail portions extending between the individual rail intersections as integral units, means to move the rail portions to form continuations of the rails of the intersecting tracks, and removable parts on the movable rail portions at said rail intersections.
- 15 8. In a railroad intersection, in combination with a pair of intersecting tracks, vertically movable rail portions extending as integral units between the individual rail intersections, said movable rail portions being interlocked with the rails of the intersecting tracks and with each other at the rail intersections, means to move the rail portions vertically to form continuations of the rails of either one or the other of said tracks, means to support the rail portions in position to form continuations of the rails of both tracks, and removable blocks at the ends of each rail portion adapted by their removal to leave open spaces adjacent to the rail intersections for passage of flanged wheels over both tracks.
9. In a railroad intersection, in combination with a pair of intersecting tracks, vertically movable rail portions extending at integral units between the individual rail intersections and adapted to form continuations of the rails of the intersecting tracks, and removable blocks at the ends of the ver-

tically movable rail portions whose removals form open spaces at the rail intersections for 40 passage of flanged wheels on both tracks.

10. In a railroad intersection, in combination with a pair of intersecting rails, mechanism adapted to form a continuation of either one or the other of the rails at their 45 intersection, said mechanism including means for simultaneously opening flange spaces at the sides of both the rails at the rail intersection.

11. In a railroad intersection, in combination with a pair of intersecting tracks, mechanism adapted to form a continuation of either one or the other of said intersecting tracks across the intersection, said mechanism including means for simultaneously 55 opening flange spaces at the sides of the rails of said tracks at the rail intersections.

12. In a railroad intersection, in combination with a pair of intersecting tracks, mechanism adapted to form a continuation of 60 either one or the other of said intersecting tracks across the intersection, said mechanism including means for simultaneously forming continuations of the rails of both said tracks and including means for simultaneously opening flange spaces at the sides 65 of the rails of said tracks at the rail intersections.

In witness that I claim the foregoing I have hereunto subscribed my name this 4th 70 day of January 1917.

EDWARD S. COBB.
